CLAIM

The ornamental design for a medical device housing, as shown and described.

DESCRIPTION

FIG. 1 is a top, left, front side perspective view of a medical device housing showing our new design;

FIG. 2 is a top elevation view thereof;

FIG. 3 is a bottom elevation view thereof;

FIG. 4 is a left side elevation view thereof;

FIG. 5 is a right side elevation view thereof;

FIG. 6 is a front plan view thereof; and,

FIG. 7 is a rear plan view thereof.

The dot-dash broken lines represent boundaries of the claimed design and form no part thereof. All other broken lines illustrate portions of the medical device housing that form no part of the claimed design.

1 Claim, 7 Drawing Sheets
